FLEXIBLE GUN MOUNT

Ralph M. Ferguson, Dayton, Ohio

Application May 17, 1933, Serial No. 671,526

8 Claims. (Cl. 89—37)

(Granted under the act of March 3, 1883, as
amended April 30, 1928; 370 O. G. 757)

The invention described herein may be manufactured and used by or for the Government for governmental purposes, without the payment to me of any royalty thereon.

- 5 The present invention relates to improvements in machine gun mounts particularly adapted for use on aircraft, the improved gun mount being designed to be mounted upon the top of the fuselage of an airplane.
- 10 Generally, the invention has reference to a simple and compact rotary support of an economical and practical nature which can be quickly and easily assembled and disassembled.

Many disadvantages have been found to exist 15 in machine gun mounts generally in use in the past. The conventional observer's gun turret used on airplane makes it impossible to obtain a complete range or arc of fire, especially under the fuselage and for a zone of considerable area, 20 for the reason that the gun socket cannot be lowered over the side of the fuselage and carried below the level of the supporting ring or rail. That leaves much to be desired in the respect 25 above noted when installed in the cockpit of the average machine, whose cockpit is ordinarily about forty inches in depth, permitting the gun sight to be followed only about forty-five degrees downwardly. Beyond or below that angle, the gun spade grip swings upwardly above the gunner's eye, and he depends entirely for sighting on 30 following the tracer bullet. This latter is often effective enough at close ranges, but it is entirely unsatisfactory at longer ranges.

The present invention aims to overcome the 35 objections above noted and at the same time provide a control for shifting the gun's position by the operator, which same can be instantly accomplished and with ease to the operator.

The primary object of the present invention 40 is to provide a mount for machine guns or the like which will allow of greater facilities in ranging and firing of the gun than heretofore, especially without exposing the gunner's body any more than necessary.

45 A further object of the present invention is to provide in a gun mount of this character a gun mount mechanism including a recoil absorption device adapted to cushion the gun's recoil during fire and thereby protect to a greater extent the gunner and still permit greater accuracy in firing.

A still further object of the present invention 50 is to provide in a gun mount of the character referred to, a supporting ring or rail upon which the gun is mounted and carried by means of a truck type carrier movable horizontally over its

supporting rail and in which a single hand operated control lever is adapted to effect a release of the carriage from the supporting ring or rail.

A still further object of the present invention 5 is to provide a carrier with an adapter upon which the gun is mounted and including a compensating device to assist in balancing the weight of the gun when the gun and adapter are moved fore and aft with respect to the carriage.

A still further object of the present invention 10 is to provide in a gun mount of this character, a gun mounting mechanism including a canting mechanism which permits of canting of the gun angularly through sufficient arcs to easily maintain the correct relation between gun sight position and the gunner's line of vision.

15 With the above and other objects in view, the invention consists in the novel construction, combination and arrangement hereinafter fully described, illustrated and claimed.

In the drawings:

Fig. 1 is a side view of the gun mount and supporting rail as installed in the gun turret of 20 an airplane.

Fig. 2 is an enlarged side view partly in section 25 of the gun adapter mechanism and gun carriage.

Fig. 3 is a sectional view taken on the line 3—3 of Fig. 2.

Fig. 4 is a sectional view taken on the line 4—4 30 of Fig. 3.

Fig. 5 is a front elevation partly in section of the gun mounting yoke.

Fig. 6 is a section, showing an enlarged portion 35 of Fig. 2.

Referring more particularly to the drawings wherein corresponding parts are designated by like numerals throughout the several views thereof, numeral 10 indicates a fuselage structure of 40 an airplane containing the usual gunner's cockpit around which is placed a fixed supporting ring or rail 11 for the gun mount. It will be noted that the gun mount is located on the airplane fuselage over the gunner's cockpit from which position the 45 gunner trains the piece in all directions. By observing Fig. 1, it will be noted that the fixed ring or rail is supported on arms 12a secured to the fuselage by bolts 12 or in any other desired manner. It should also be noted that the rear portion of the ring is elevated substantially above the forward portion of the ring. By elevating the ring or rail in the manner illustrated in Fig. 1, it will be apparent that when the gun carriage to be hereinafter set forth in greater detail is 50 55

mounted on the rail it will tend under the action of gravity to move forwardly toward the lower forward end of the rail. This tendency of the carriage to move forwardly on the ring compensates for the tendency of the gun carriage to be violently forced backward due to the action of the air stream, especially when the gun is being fired broadside with respect to the air stream.

The gun mount comprises a gun carriage, designated generally by the numeral 13, and a gun support designated generally by numeral 14. The carriage 13 is generally U-shaped and comprises a body portion or back plate 15 and upper and lower arm portions 16 and 17 respectively extending outwardly from the body portion 15 which are adapted to embrace the rail 11 as shown in Fig. 2. These arm portions contain anti-friction rollers 18 which are rotatably mounted in suitable truck-type supports carried by said arm portions 16 and 17 and bear against the top, bottom, and opposite sides of the rail 11 as illustrated in Fig. 4. This enables the carriage to be moved longitudinally of the rail with perfect freedom.

In order to hold the carriage stationary when firing, I make use of a pair of clamping members indicated by numeral 19, said clamping members being connected by pivots 20 to the arm portions 16 and 17, respectively of the carriage 13. As will be noted by referring to Fig. 2, these clamping members extend over and embrace the extremities of the rail 11. The inner ends 21 of these clamping members are pivotally connected to the toggle joint links 22 shown in Fig. 4. The links 22 are arranged to extend toward one another in opposing relation, each being provided with a projecting lug portion 23 which contacts with set screws 24, screwed through threaded openings in the back plate 15 of the gun carriage. By turning the set screws 24, wear may be compensated for between the clamping members and the rail 11. The free ends of the links 22 are provided with lips 25 and 26 which are engaged by a pair of floating cams 27 carried by transversely extending stub shafts 28 suitably journaled in the body portion of the gun carriage. The outer ends of the stub shafts 28 extend through the sides of the body portion of the carriage and have conveniently attached thereto a handle indicated by the numeral 29, depending downwardly, and in the normal position out of the way of the gunner. As shown in Fig. 3, coiled springs 30 are mounted on the stub shafts 28 and have their one ends attached to said stub shaft and their other ends securely anchored to the body portion of the carriage 13 and to normally maintain the handle in the downward position. It should also be noted that the clamping members have secured therebetween a spring 31 in order that the lips 25 and 26 of the links 22 will be at all times in operative engagement with the cams 27. Moving the handle upwardly tends to release the clamping members and permits the gun carriage to be adjusted longitudinally with respect to the ring or rail 11. Upon releasing the handle, the clamping members are restored to their clamping position through the action of the springs 30. Thus, by means of a single control handle located on the gun carriage, where a greater leverage is obtained for moving the carriage along its supporting rail, either the gun support or carriage may be released to permit the gunner to swing the gun to any desired firing position.

The gun support 14 comprises generally adapter arms 32 provided with a lower bearing portion 33 which is journaled upon a horizontally dis-

posed shaft 34 provided in the upper end of the gun carriage 13. Intermediate its ends the bearing portion 33 is formed with gear teeth 35 adapted for meshing engagement with the gear teeth of a vertically extending gear rack 36. The lower end of the gear rack 36 is provided with an internal splined bore 37 within which is mounted a rotatable splined shaft 38. The lower end of this shaft is formed with a circular flanged portion indicated by numeral 39. The upper half of the peripheral edge of this flanged portion 39 is formed with right hand ratchet teeth 40, while the lower half is provided with left hand ratchet teeth indicated by numeral 41.

Control of this ratcheting arrangement is effected through manipulation of a plunger 42, formed with the lugs 43 and 44 respectively which are adapted to engage in the ratchet pieces 40 and 41 heretofore mentioned. To accomplish such purpose the rear end of the plunger 42 is operatively engaged by a coiled spring 45, the other or opposite end of said spring bearing against the end of a bore 46 formed in the lower end of the carriage as shown in Fig. 2. The plunger is operated through the medium of a flexible control cable indicated by numeral 47 which extends through the casing 48 and terminates in a trip mechanism generally indicated by numeral 49, positioned on the spade grip 50 of the machine gun where it is convenient for the gunner to effect a release of the ratchet mechanism without detracting his attention while training and firing the gun.

The gear rack 36 is also provided with an upper shoulder 51 which bears against a floating collar 52. At its lower end the gear rack is provided with a flanged portion 53 normally bearing against a shoulder 54 formed internally in a floating bushing 55 which surrounds the lower end of the rack 36. In a similar manner the bushing 54 is formed with a lower shoulder 56 as shown in Fig. 6. Intermediate this shoulder 56 and the collar 52, a compression spring 57 is interposed, the spring being so designed that when the gun adapter arm 32 is in the normal firing position shown in Fig. 1, the spring is carried freely between shoulder 56 and floating collar 52 and under no compression. By means of such arrangement, should the gunner desire to train the gun upwardly in order to fire upon an object above the airplane, the adapter arm will be moved rearwardly and downwardly in the dotted line position, as illustrated in Fig. 1. At the same time the gear rack 36 will be moved vertically upwardly in the dotted line position illustrated in Fig. 2. When this occurs, the shoulder 56 will be moved upwardly by the gear rack. At this time the upper end of the compression spring is held in fixed position by the floating collar 51 and consequently the spring will be compressed. On the other hand, with the gun adapter arm in the normal firing position as illustrated in Fig. 1, should the gunner desire to train the gun downwardly in order to fire upon an object beneath the airplane, the adapter arm will be moved forwardly and downwardly into the dot and dash position illustrated in Fig. 1. At this time the upper shoulder 51 in moving downwardly as the gear rack is moved downwardly will bear against the floating collar 52. At this time the lower end of the compression spring is held against downward movement by the lower shoulder 56 heretofore mentioned. Consequently, in moving downwardly, the gear rack tends to compress the spring in the same manner as before described. Either up or

down movement of the gear rack will impart a rotational movement to the shaft 38 and by reason of the ratchet mechanism heretofore described, the adapter arm will be locked in either a forward position or a rearward position as the gunner desires which same is controlled or locked in position by actuation of the plunger 42 carrying lugs 43 and 44 into or out of engagement with the ratchet teeth.

Hence, it will be seen that either forward or rearward movement of the adapter arm with respect to the carriage will effect a compression of the spring 57 and should the gunner desire to return the gun to normal firing position, this same may be accomplished through the medium of the trip mechanism heretofore mentioned. The adapter arm 32 carries a post 58 as illustrated in Fig. 2 which is vertically disposed with respect to the adapter arms 32 and is provided with a bearing portion 59. A gun yoke 60 is provided which is formed at its lower end with a journal 61 which fits within the bearing portion 59 heretofore mentioned. The gun yoke is generally fork-shaped and includes the arm portions 62 and 63 which are adapted to extend upwardly along each side of the gun. The upper ends of the arms of the gun yoke are provided with horizontally disposed bearing portions 64 and 65 within which is adapted to be received the journals 66 which extend diametrically outwardly from a mounting ring generally indicated by numeral 67. This mounting ring 67 is formed with a forwardly extending tubular portion 68 over which is adapted to be slidably mounted the front end of a mounting yoke 69 including spaced side plates 70 and 71, each of these side plates being provided with an inwardly extending lug 72 and 73 respectively adapted for receiving the gun trunnions indicated by the numeral 74. The rear end of the mounting ring 67 bears against the gun in the manner illustrated in Fig. 2. A compression spring 75 surrounds the tubular portion 68 of the mounting ring, the forward and rearward ends of which are positioned under compression against the rear end of the mounting yoke 69, and the annular flange 76 formed on the mounting ring 67. This arrangement permits of a canting action of the gun right or left from its normally horizontally disposed position, as shown in dotted outline in Fig. 5, throughout sufficient arcs to easily maintain a correct relation between the gun sight position and the gunner's line of vision. At the same time the gun recoil during firing is substantially completely absorbed through the medium of the compression spring 75.

It will be seen that I have provided a mount which is extremely well suited for large guns where the gun is of unusual length, and where it is extremely desirable that the gun be capable of being maneuvered quickly and easily in any direction in order to train the gun upon the object to be fired upon.

By means of the construction herein shown and described, the gunner is able to train the gun downwardly over the fuselage to the proper level to enable his eye to follow the sight over the spade grip when flying straight downwardly and even underneath the fuselage. A high position of the machine gun may also be obtained by moving the adapter arm rearwardly in the manner heretofore described in order to permit the gunner to fire upon objects above the plane. The gun weight is at all times counterbalanced by the spring 57, while the clamping members enable the gun carriage and gun support to be

clamped and released instantly at the will of the operator and by an intuitive movement of the control handle. Though primarily intended for the gun grip of an airplane, or other craft, it will be readily seen that the gun mount may be fixed to any convenient sight, whether a building, a ship, or otherwise, and it will work in substantially the same way and will have the same advantages.

This invention also enables the gunner to keep more within the airplane body than has heretofore been feasible up to the present time; there is no need for him to throw his head and shoulders well out for the purpose of balancing the gun against the wind pressure when flying in order to enable him to swing the gun around; this extra head resistance slows the machine in practice, whereas, with my invention very little head resistance is effected when in action, and practically none when the gun is out of action, because of the compact arrangement of the entire apparatus.

The several features of the present invention are not limited to the precise construction and arrangement of devices described, and it is to be understood that many modifications and changes may be made therein without departing from the spirit of this invention or of the bonds in the appended claims.

What I claim is:

1. In a gun support for use on aircraft, the combination of a supporting rail, a U-shaped carrier movable along said rail, a single spring actuated controlling device operating automatically to lock said carrier in adjusted position relative to its supporting rail and embodying spring controlled clamping members oppositely disposed on the free ends of said U-shaped carrier adapted to embrace and yieldingly engage the upper and lower surfaces of said rail, a hand operated lever pivotally mounted on said carrier, toggle joint connections between said lever and clamping members, camming elements operated by movement of said hand lever adapted for simultaneously operating said toggle joint connections to lock or unlock said clamping members, and means for adjusting said toggle joint connections to effect an equalized clamping action of said clamping members.

2. In a gun support for use on aircraft, the combination of a supporting rail, a U-shaped carrier movable along said rail, a single spring actuated controlling device operating automatically to lock said carrier in adjusted positions relative to its supporting rail and embodying clamping members oppositely disposed on the free ends of said U-shaped carrier adapted to embrace and engage the upper and lower surfaces of said rail, a hand operated lever pivotally mounted on said carrier, toggle joint connections between said lever and clamping members, camming elements operated by movement of said hand lever adapted for simultaneously actuating said toggle joint connections to lock or unlock said clamping members, and means for adjusting said toggle joint connections to effect an equalized clamping action of said clamping members.

3. In a gun support for use on aircraft, the combination of a supporting rail, a U-shaped carrier movable along said rail, means operating automatically to lock said carrier in adjusted positions relative to its supporting rail and em-

- bodying clamping members oppositely disposed on the free ends of said U-shaped carrier adapted to embrace and engage the upper and lower surfaces of said rail, and means pivotally mounted on said carrier for supporting said gun thereon, said means including a pinion and rack arrangement permitting angular movement of said gun about a horizontal axis, a counterbalancing means actuated by movement of said gun to compensate for the weight of said gun, said means comprising a single yieldable element mounted in a manner such as to be increasingly compressible when said gun is moved angularly in fore-and-aft directions.
4. In a gun support for use on aircraft, the combination of a supporting rail, a U-shaped carrier movable along said rail, means operating automatically to lock said carrier in adjusted positions relative to its supporting rail and embodying clamping members oppositely disposed on the free ends of said U-shaped carrier adapted to embrace and engage the upper and lower surfaces of said rail, an adapter arm pivotally mounted on said carrier for movement about a horizontal axis to permit angular movement of said gun from normal firing positions, a pinion carried by said adapter arm, a gear rack engaging said pinion, a single compressible element housed in said carrier, and means operatively associated with said element and controlled by movement of said gear rack for compressing said spring and compensate for the weight of the gun when moved angularly fore-and-aft from its normal firing position.
5. In a gun support for use on aircraft, the combination of a supporting rail, a U-shaped carrier movable along said rail, means operating automatically to lock said carrier in adjusted position relative to its supporting rail and embodying clamping members oppositely disposed on the free ends of said U-shaped carrier adapted to embrace and engage the upper and lower surfaces of said rail, an adapter arm pivotally mounted on said carrier about a horizontal axis to permit angular movement of said gun from normal firing position, means for counterbalancing the weight of said gun and for automatically turning said gun to normal firing position, said means comprising a pinion, a gear rack engaging said pinion, a single compressible element, a mechanism operatively associated with said element and controlled by movement of said gear rack for compressing said spring and compensate for the weight of the gun when moved angularly fore-and-aft from its normal firing position, and means for releasably securing said adapter arm in any position of angular adjustment of said carrier.
6. In a gun support for use on aircraft, the combination of a supporting rail, a U-shaped carrier movable along said rail, means operating automatically to lock said carrier in adjusted positions relative to its supporting rail and embodying clamping members oppositely disposed on the free ends of said U-shaped carrier adapted to embrace and engage the upper and lower surfaces of said rail, an adapter arm mounted for movement about a horizontal axis on said carrier to permit fore and aft movement of said gun from normal firing position, counterbalancing means cooperating with said carrier to compensate for the weight of said supported gun, said means comprising a single compressible element housed in said carrier, means operatively associated with said element and controlled by movement of said adapter arm by compressing said spring and compensating for the weight of the gun when moved angularly fore-and-aft from its normal firing position, and a double acting ratchet mechanism cooperating with said compensating means for locking said adapter arm in any fore and aft position with respect to said carrier.
7. In a gun support as set forth in claim 6, said double acting ratchet mechanism being characterized by including a remote control device positioned adjacent the trigger mechanism of said gun.
8. In a gun support for use on aircraft, the combination of a supporting rail, a U-shaped carrier movable along said rail, means operating automatically to lock said carrier in adjusted position relative to its supporting rail and embodying clamping members oppositely disposed on the free ends of said U-shaped carrier adapted to embrace and engage the upper and lower surfaces of said rail, an adapter arm mounted for movement about a horizontal axis on said carrier to permit fore and aft movement of said gun from normal firing position, compensating means for counterbalancing the weight of said gun and for automatically effecting a return movement to normal firing position, said means comprising a pinion, a vertically disposed gear rack engaging said pinion, a single compressible element housed in said carrier, means operatively associated with said element and controlled by movement of said gear rack for compressing said spring and compensate for the weight of the gun when moved angularly fore-and-aft from its normal firing position, and a double acting ratchet mechanism operated by movement of said gear rack for locking said adapter arm in any fore and aft position with respect to said carrier.

RALPH M. FERGUSON.
